UNITED STATES PATENT OFFICE.

EDWD. RICHMOND, OF BROOKLYN, ASSIGNOR TO HIMSELF AND JOHN F. ORCUTT, OF STATE OF NEW YORK.

IMPROVED WHIP-RACK.

Specification forming part of Letters Patent No. 58,480, dated October 2, 1865.

To all whom it may concern:

Be it known that I, EDWARD RICHMOND, of Brooklyn, Kings county, New York, have invented a certain new and Improved Rack for Whips and other articles; and I do hereby declare the following to be a full, clear, and exact description of the same, reference being had to the accompanying drawings, in which—

Figure 1 represents a top view of my improved whip-rack; Fig. 2, a section on the line *x x*, Fig. 1; and Fig. 3, a section on the line *y y*, Fig. 1.

Great difficulty has heretofore been experienced for retaining, for any length of time, a straight top on a whip, on account of the limber character of the whip and the consequent inability of the top to sustain its weight. It has been customary to meet this difficulty by suspending the whip, when not actually in use, by its tip or upper end, so that when thus suspended its own weight will tend to keep the whip straight. In order to do this, however, it has been usual to knot the lash or to tack it up, or to form a slip-knot or sling in it, in order to attach it securely to the nail or other support from which it hangs. This proceeding is not only inconvenient, but injurious to the whip, as the lash thereby becomes worn or damaged and misshapen, so as to require frequent renewal.

The object of my invention is to construct a rack from which a whip may be easily suspended by its tip without injury. For this purpose I take two plates of wood or metal, with an interposed sheet of vulcanized rubber, and in the edge of such plates and rubber sheet, I cut or otherwise form notches or openings, as hereinafter described, under such an arrangement that the notch in the wooden plates shall be somewhat larger than the corresponding slot or opening in the rubber, so that the tip or lash of the whip, when placed in such opening and pushed back in it may be held and retained by the rubber.

I am aware that racks, formed of wooden plates, with an interposed sheet of rubber, provided with circular holes or perforations, have been heretofore used; but the object of such racks is to suspend or hold the whip by the butt or at some point near the butt, differing entirely from the object I have in view, which is to sus-

pend a whip by its extreme tip or lash, so that the whole weight of the whip may be sustained by the lash, which is thereby kept in a straight and upright form, and is prevented from becoming bent or misshapen, as above described. The notch or slot in the rack invented by me differs, also, materially in form and construction from that of the ordinary rack, above referred to, for, being open at its outer end, it admits of the lash being placed and pushed back therein with the greatest facility.

To enable others to fully understand my invention and the manner in which the same is, or may be, carried into effect, I will now proceed to describe it by reference to the accompanying drawings, which represent a rack constructed in accordance with my invention, having formed in it, also, the ordinary holes for holding the whip by its butt, as above described, which form no part of my invention. The whip rack or frame there shown consists of two plates of wood or metal, *A A'*, with an interposed sheet of vulcanized rubber, rubber cloth, or other elastic substance, *B*. In the two plates circular holes or perforations *a a'* are formed at suitable distances from each other, and of any desired size to suit the size of the holes in the rubber cloth or other elastic substance, as hereinafter explained. These perforations in the plates *A A'* are so made that when the two plates are placed together, the holes *a a'* shall correspond, as shown in Figs. 2 and 3. In the edges of the plate also are cut or otherwise formed slots or openings *c c'*, arranged alternately or in quincunx order with respect to the holes *a a'*. Between these two plates is interposed a sheet of vulcanized rubber, rubber cloth, or other elastic substance, *B*, which is held tightly by means of the screws *m* or other suitable devices for binding together the upper and under plates *a a'*. In order to effect a saving of rubber, instead of a continuous sheet, as described, rubber disks or plates, whose circumference is larger than the openings *a* and *c*, to which these are applied, may be employed, the disks being cemented or otherwise secured at their outer edges to one or both the plates *A A'*.

By this arrangement, it will be seen that where the holes *a a' c c'* are formed, the rubber *B* is not covered by the plates. At each

point where the sheet is thus left uncovered by the circular opening $a a'$, a hole or opening, b , of suitable size, is made concentric with the openings $a a'$, and in like manner slots b' are formed at the edge of the sheet where it is exposed by the openings $c c'$ of the plates A A'. The slots b are so formed as to have a V-shape, tapering from their front toward their rear ends. In these openings b and b' the whips or other articles to be suspended are inserted, the former being used if the whips are to be suspended from their butts—the latter if they are to hang by their tops.

In order to enable the elastic substance to conform more readily to the size and shape of the whip, one or more slits, d and e , are made in the edge of the elastic substance which surrounds the openings. These slits d , at the openings b' , may be of any suitable length, and they may vary in number, being either more or less numerous than is represented in the drawings, though I have found the number there shown sufficient for all practical purposes.

When it is desired to suspend the whip C from its butt, the top or lash is inserted from above through the opening b , and then the whip is drawn through the opening until it has reached the position desired; or the butt of the whip may be pushed up through the opening b .

The rubber B, by reason, both of its inherent elasticity and of the slits d , conforms readily to the shape of the whip, yielding to the whip as it is drawn through the holes b , yet at the same time embracing it tightly, so as to hold it in place, whether the whip be inserted as far as the handle or butt, as shown in Fig. 2, or whether it be only inserted half as far.

If the whip is to be hung by its tip or lash, the V-shaped slots b' are employed. The tip or small end of the whip is placed or inserted in one of these slots and is then forced back in it or drawn through it until the whip is held tightly and firmly, as shown in Fig. 3. The slot e in this case has the same functions as the slits d around the openings b . It causes

the rubber to yield with more facility to the whip, without impairing in the least the ability of the rubber to hold the whip in place.

The size of the holes and slots $a a' c c'$ should bear such relation to the size of the openings $b b'$ that, while sufficient to admit the whip-handle and to afford a sufficient degree of elasticity to the rubber, it shall not be so great as to give too much freedom to the rubber or to prevent it from holding the whip-handle tightly.

It is apparent that the whips C can be removed from the rack or frame with as much facility as they are inserted therein.

To one of the edges of the frame or rack is secured an upright plate, D, by screws m or otherwise, and by means of this plate the rack is attached to the wall or other place where it is required to be used, as represented in Fig. 2, the screws p holding the entire frame firmly to the wall E. Brackets or any other suitable device, however, may be used to fasten the rack to the wall.

Having described my invention, what I claim, and desire to secure by Letters Patent, is as follows:

1. In a rack or frame for holding whips, composed of plates of wood or other suitable material, with an interposed sheet of rubber or other elastic substance, as specified, the V-shaped openings or slots formed in the edge of said rack for holding the whip by its tip, the same being constructed and arranged substantially as herein described.

2. As a new article of manufacture, a rack or frame composed of the materials herein described, in which the circular holes a and c are combined with the V-shaped openings formed in the edge of said rack, the whole being constructed and arranged for operation, substantially as shown and set forth.

In testimony whereof I have signed my name to this specification before two subscribing witnesses.

E. RICHMOND.
